UNITED STATES PATENT OFFICE.

FRED D. HOLDSWORTH, OF CLAREMONT, NEW HAMPSHIRE, ASSIGNOR TO SULLIVAN MACHINERY COMPANY, A CORPORATION OF MASSACHUSETTS.

COMPRESSOR-CONTROLLING MECHANISM.

1,408,943.

Specification of Letters Patent.

Patented Mar. 7, 1922.

Application filed May 21, 1917. Serial No. 169,971.

To all whom it may concern:

Be it known that I, FRED D. HOLDSWORTH, a citizen of the United States, residing at Claremont, in the county of Sullivan and State of New Hampshire, have invented certain new and useful Improvements in Compressor-Controlling Mechanisms, of which the following is a full, clear, and exact specification.

10 My invention relates to compressor controlling mechanisms.

It has for its object to control a compressor in an improved manner and to provide improved means whereby the compressor is automatically loaded or unloaded in accordance with the requirements of its service. A more specific object of my invention is to provide improved valve controlling mechanism especially adapted to multi-stage machines, whereby as a result of pressure changes arising from the closure of the main unloader or intake controlling valve, the inlet valves of the compressor are opened to unload the compressor, these valves being thereafter closed as the pressure conditions again vary. These and other objects of my improved construction will, however, hereinafter more fully appear.

In order that my invention may be fully and clearly disclosed, I have illustrated in the accompanying drawings one embodiment which the same may assume in practice.

In these drawings,—

Fig. 1 is a side elevation of a compressor equipped with my improvement, portions of the same being broken away to facilitate illustration.

Fig. 2 is an enlarged detail sectional view of the intake controlling valve and its connections, the valve being shown in closed position.

Fig. 3 is a transverse sectional view taken on line 3—3 of Fig. 2.

Fig. 4 is a detail sectional view of one of the pilot valves.

In this illustrative construction, I have shown a multi-stage compressor mounted upon a suitable base and comprising a low pressure cylinder 1 having a piston 2 movable therein and connected through a piston rod 3 with an axially disposed piston 4 in a high pressure cylinder 5. As shown, each of the cylinders 1 and 5 is provided with inlet valves 6 of the suction type and with discharge valves 7 of usual construc-

tion, only one of each set of valves being shown for purposes of illustration. Operatively connected between the cylinders is also the usual intercooler 8, and operatively connected to the high pressure cylinder 60 through a suitable connection 9 is a receiver 10. Disposed in the intake 11 leading to the low pressure cylinder is also an unloader valve 12 of usual construction, normally held open by a spring 13 and adapted to be 65 closed by fluid pressure through means hereinafter described, or manually by the adjustment of a suitable adjusting mechanism 14.

In my improved construction, it will be noted that this unloader valve 12 is connected through a connection 15 with the receiver 10, the air supply from the receiver being conducted to an annular space or chamber 16 formed in the upper part of the valve casing 17. This space, as shown, 70 extends around the manually operable adjusting means 14 and has connected thereto a passage or pipe 18 leading to a pilot valve 19, which may be of any standard construction, such as the standard Jarecki or Judson 80 pilot valve, adapted to respond to a predetermined receiver pressure. As shown, this valve 19 communicates with a passage 20 leading into a central axially disposed chamber 21 disposed within the chamber 16, 85 wherein the pressure may act upon the upper surface of the valve 12 in such a manner as to depress the same and close the intake. As in the usual operation of such an unloader valve, when the receiver pressure 90 rises above a predetermined point, the same actuates the valve 19 and admits the receiver pressure to the chamber 21 so that as a result the main unloader valve 12 is depressed against the pressure of its spring 95 13 to close the intake 11. Conversely, when the receiver pressure falls below a predetermined level the air in this chamber 21 will be exhausted through the valve 19 to the atmosphere. It will also be noted that in 100 this construction I have provided a pipe 22 which communicates with the chamber 16 and acts as a drain for any liquid accumulated therein.

Obviously, through the operation of the 105 mechanism just described, the intake 11 will be opened or closed in accordance with variations in pressure in the receiver 10. As soon, however, as the valve 12 is closed, it will be obvious that since no air is supplied 110

2

to the compressor, the continued operation thereof will result in the progressive formation of a vacuum in the compressor spaces, the vacuum first being formed in those spaces on the inside of the valve 12 so that practically as soon as the valve 12 is closed the low pressure cylinder will be unloaded. The suction valves 6 for the high pressure cylinder will remain operative, however, and it is desirable for them to do so for a short time for reasons of efficiency, in order that the air then in the compressor may be delivered to the receiver. In my improvement, I have provided improved means whereby these last mentioned suction valves may be lifted from their seats, the progressive drop in pressure in the compressor following from the closure of the intake valve 12 being utilized in bringing about this movement of the suction valves.

As shown, these suction valves 6 of the high pressure cylinder are provided with the usual spring pressed valve stems, and beneath the same are located suitable pistons or plungers 23 movable in suitable cylinders 24, of which only one is shown for purposes of illustration. These cylinders 24 are in turn connected through a pipe connection 25 with a second pilot valve 26 operatively connected to the chamber 16 through a pipe connection 27, and also connected through a pipe connection 28, communicating with a removable dome or cover member 29 on the valve 26, with a point in the compressor where the pressure is reduced a short time after closure of the intake valve 12. Herein, I have shown this connection 28 to be made to a chamber 30 disposed within one of the pillar supports 31 for the high pressure cylinder and communicating in the usual manner with the intercooler 8 so that the pressure in this chamber varies with the pressure in the intercooler. Obviously, however, if quite such a long delayed unloading of the high pressure cylinder is not desired, this connection may be made at a point at the compressor side of the intake valve 12 through a suitable connection 32, and I have accordingly shown the same connected to each of these points, suitable controlling valves 33, 34 being provided in the connections 28, 32 so that upon opening its valve either of the same may be used, the other then being cut out by closing its valve.

Obviously, as a result of this construction, when either the pressure in the chamber 30 or at the compressor side of the intake controlling valve 12 drops below a predetermined amount, the pilot valve 26 will be operated in such a manner as to open communication from the receiver 10 to the chamber 17 and through the pipe connection 27 to the connection 25 and the pistons or plungers 23 for operating the suction inlet

valves 6 of the high pressure cylinder. As a result of the fluid supply through these connections, these valves 6 will be lifted from their seats in such a manner as to unload the compressor. When, however, the receiver pressure falls to such an extent as to cause the unloader valve 19 to be operated in a well known manner to exhaust the pressure from the space 21 above the intake controlling valve 12, this valve 12 will be opened by its spring 13 in such a manner as to permit the pressure in the compressor to be built up. Thereupon, due to the increase in pressure supplied through the connection 28 to the top of the pilot valve 26, that valve 26 will be operated in such a manner as to open the connection 25 to the atmosphere in a well known manner through ports 35, thereby exhausting the air from beneath the plungers 23 and permitting the suction valves 6 of the high pressure cylinder to seat and load the compressor so that it may again supply pressure fluid to the depleted receiver.

The unloading mechanism including the pilot valve 26 and its dome-shaped cover 29, which herein is connectible either to the chamber 30 or the compressor side of the intake controlling valve 12, has been described in my co-pending application Serial No. 134,452, filed Dec. 1, 1916, but in order that the operation of the same in my present invention may be clearly understood, the description of this mechanism will be repeated herein, it being understood that save for the cover 29, the valve 19 may be of the same construction as the valve 26. This valve 26 is shown in an enlarged view in Fig. 4. As illustrated therein, it preferably comprises a suitable casing having a diaphragm 36 disposed across a chamber 37 in its bottom. To this chamber 37 air at receiver pressure is admitted from the connection 27 communicating with the receiver 10 through the chamber 16. Disposed below this diaphragm 36 in this chamber, is a vertically disposed spring pressed hollow plunger 38 having oppositely disposed ports 39 at its upper end communicating with the chamber 37. Disposed adjacent the open lower end of this member 38 is also a ported disk valve 40 normally held in elevated position by a spring 41, in such a manner as normally to engage the lower end of the depressed plunger 38 and thereby close communication between the receiver and a port 42 leading to the connection 25. As usual, a series of ports 43, communicating with the ports 39 which lead to the atmosphere, is also disposed adjacent the valve 40 and, due to the action of the spring 41, the ports in the valve 40, and the spaces around the valve, these ports 43 are normally in communication with the connection 25 to exhaust the air therefrom. Disposed above this dia-

phragm and acting on the opposite surface thereof, is a plunger 44, normally held in depressed position by a coiled spring 45 which acts between the plunger and an upper 5 adjustable cap member 46 having a port 47 therein communicating with the space within the dome member 29. In practice, this spring 45 is of sufficient strength when added to the pressure in the compressor to 10 hold the diaphragm 36 depressed against the receiver pressure. When, however, the pressure in the compressor is decreased, as after closure of the intake, these opposing pressures are unbalanced in such a manner 15 as to permit the diaphragm 36, the plunger 38, and the valve 40, to be raised to close communication between the ports 35 and the connection 25 and permit the air from the receiver to pass through the plunger 38 and 20 the ports in the valve member 40 through the opening 42, to the connection 25 in such a manner as to raise the valve plungers 23 of the high pressure inlet valves 6 and lift the latter from their seats to unload 25 that cylinder. Conversely, when the pressure in the compressor is built up, as after the intake controlling valve is again opened, the diaphragm 36 is depressed and the plunger 38 again lowered to normal position to open 30 communication between the ports 35 and the connection 25 and thus cause the air beneath the plungers 23 to be exhausted so that the valves 6 of the high pressure cylinder may seat and thereby load that cylinder.

35 In my improved construction, it will be noted that through the provision of the dome 29 and the connection of the same to the chamber 30 or to the compressor side of the valve 12, I have provided means where- 40 by this valve mechanism may be made responsive to the variations in the pressure within the compressor, and therefore operate to control the flow through the connection 25 in accordance with variations in pressure 45 arising from the opening or closing of the intake. In this construction it will further be noted that, as distinguished from the construction shown in my previous application mentioned above, I dispense with separate 50 inlet valve actuating plunger mechanism for the low pressure cylinder, and utilize a pilot valve to control the main unloader valve or intake controlling valve.

55 In the earlier application among other features, means for effecting a stepped unloading of the cylinders of a multiple cylinder compressor is broadly set forth and claimed, including means for controlling the loading and unloading of one stage con- 60 trolled by effects produced by the loading or unloading of another, or means for unloading the low pressure stage of a compressor, and means for unloading or re- 65 loading a higher pressure stage governed as to both its functions by the combined effects

of the discharge pressure of that stage during normal loaded running and the pressure in said compressor at a point between the suction side of that stage and the intake of said compressor. Therein I also claim cer- 70 tain sub-combinations relating to the structure of the H. P. pilot control, along with other features.

While I have in this application specifically described one embodiment which my 75 invention may assume in practice, it is to be understood that the same is not limited thereto, but may be modified and embodied in various other forms without departing from its spirit, it being my intention to in- 80 clude all such modifications within the scope of the appended claims.

What I claim as new and desire to secure by Letters Patent is:

1. In combination, a multistage compres- 85 sor, and means for unloading the several stages of said compressor at variable intervals comprising means for unloading one of said stages, and means for subsequently unloading another of said stages including a control member actuated by compressor discharge pressure and operative in opposite positions thereof to effect loading and unloading of said last mentioned stage, said member being movable substantially instantaneously between its operative positions, and means for varying the instant of movement of said member. 90

2. In combination, a compressor having a plurality of stages, unloading means co- 100 operating with each of said stages, means cooperating with the unloading means for one of said stages for delaying the operation thereof after the operation of said other unloading means including a plurality of 105 connections with said compressor beyond said first mentioned unloading means, and means for selectively controlling said connections to vary the delay in operation.

3. In combination, a compressor having a 110 plurality of stages, unloading mechanisms cooperating with each of said stages, means responsive to receiver pressure for controlling the operation of one of said mechanisms, means for controlling the operation 115 of another of said mechanisms responsive to receiver pressure and having a connection with said compressor at a point beyond said first mentioned unloading means, and means for varying said point of connection. 120

4. In combination, a compressor having a plurality of compression chambers, unloading mechanism for each of said chambers, controlling means each independent of the other for each of said unloading means and 125 having a common source of operating medium, and means for causing said means to operate sequentially and with variable intervals between their operations.

5. In combination, a multistage com- 130

pressor having a plurality of compression chambers and an intake, intake controlling mechanism, inlet valve mechanism for a compression chamber constituting a stage above the first stage, and controlling mechanism for said inlet valve mechanism comprising means operative to render the latter inoperative including a controlling valve operated by compressor discharge pressure and controlled by variations in pressure arising from the closure of said intake.

6. In combination, a compressor having a plurality of compression chambers and an intake, intake closing mechanism, and automatically acting means including a plurality of inlet valves controlled by variations in pressure arising from the closure of said intake and operated by receiver pressure for unloading one of said compression chambers.

7. In combination, a compressor having a plurality of compression chambers and an intake, intake closing mechanism, and automatically acting means operated by terminal pressure and controlled by variations in pressure arising from the closure of said intake to effect a delayed unloading of one of said chambers.

8. In combination, a compressor having a plurality of valved compression chambers and an intake, intake closing means effective upon closure to unload one of said chambers, and means operated by terminal pressure and controlled by variations in pressure arising from closure of said intake for effecting a relatively retarded unloading of the other compression chamber.

9. In combination, a compressor having a plurality of valved compression chambers and an intake, intake closing means effective upon closure to unload one of said chambers, means operated by terminal pressure and controlled by variations in pressure arising from closure of said intake for effecting a relatively retarded unloading of the other compression chamber, and means for varying the degree of retardation.

10. In a compressor controlling mechanism, the combination including a multi-stage compressor having a plurality of compression chambers and an intake, inlet valves for the high compression chamber thereof, intake closing mechanism, and means responsive to a change in pressure condition arising from the closure of said intake closing mechanism for controlling said inlet valves.

11. In a compressor controlling mechanism, the combination including a multi-stage compressor having a plurality of compression chambers and an intake, suction inlet valves for the high compression chamber thereof, intake closing mechanism, and means responsive to a change in pressure condition arising from the closure of said

intake closing mechanism for unseating said suction inlet valves.

12. In a compressor controlling mechanism, the combination including a multi-stage compressor having a plurality of compression chambers and an intake, inlet valves for the high compression chamber thereof, intake closing mechanism, and means responsive to a change in pressure condition arising from the closure of said intake closing mechanism for controlling said inlet valves by the action of compressor discharge pressure.

13. In a compressor controlling mechanism, the combination including a multi-stage compressor having a plurality of compression chambers and an intake, suction inlet valves for the high compression chamber thereof, intake closing mechanism, and means responsive to a change in pressure condition arising from the closure of said intake closing mechanism for unseating said suction inlet valves by the action of compressor discharge pressure.

14. In combination, a compressor having an intake, a receiver, an intake controlling means provided with an intake controlling valve and a plurality of chambers, one of said chambers communicating with said valve and the other with said receiver, and pressure responsive mechanism controlling the supply and exhaust of pressure fluid relative to the chamber communicating with said valve and located exterior to said last mentioned chamber.

15. In combination, a compressor having an intake, a receiver, an intake controlling means provided with an intake control valve, a plurality of chambers, one of said chambers communicating with said valve and the other with said receiver, drainage means for said last mentioned chamber, and pressure responsive valve mechanism controlling a connection between said chambers and located exterior to each of them.

16. In combination, a compressor having an intake, a receiver, and intake controlling means comprising a casing having a plurality of chambers, an intake controlling valve in one of said chambers, a communication between one of said chambers and the receiver, and a connection between said last named chamber and said valve containing chamber, said connections being provided with a receiver pressure responsive controlling valve.

17. In combination, a compressor having an intake, a receiver, an intake controlling valve provided with a plurality of concentric chambers one communicating with said valve and the other with said receiver, and valve mechanism responsive to receiver pressure controlling the pressure conditions in the chamber communicating with said valve.

18. In combination, a compressor having

- high and low pressure cylinders and an intake, a receiver, intake closing mechanism responsive to receiver pressure, inlet valves for a high pressure cylinder, means for unseating said inlet valves including a connection to the receiver, and means controlling said connection responsive to pressure conditions arising from closure of the intake.
19. In a compressor controlling mechanism, the combination including a multistage compressor having an intake, inlet valves for the high pressure cylinder thereof, intake closing mechanism, pressure actuated plunger mechanism for actuating said inlet valves, and means responsive to a change in pressure conditions arising from the closure of said intake closing mechanism for supplying pressure fluid to said plunger mechanism.
20. In a compressor controlling mechanism, the combination including a compressor having high and low pressure cylinders, a receiver connected to said compressor, intake controlling mechanism responsive to receiver pressure, inlet valves for the low pressure cylinder communicating with the compressor side of said intake controlling mechanism, inlet valves for a high pressure cylinder, means for subsequently unloading said high pressure cylinder including a connection between said inlet valves of said high pressure cylinder and said receiver, and means for controlling said connection responsive to changes in pressure conditions in said compressor.
21. In combination, a compressor having high and low pressure cylinders, a receiver connected to said compressor, compressor intake controlling mechanism connected to said receiver, inlet valves for a high pressure cylinder, and means for actuating said valves to unload said cylinder including a pilot valve operatively connected to said receiver through said intake controlling valve mechanism and to the compressor spaces at a point on the compressor side of said intake controlling mechanism.
22. In a compressor controlling mechanism, the combination including a multistage compressor having an intake, inlet valves for the high pressure stage thereof, intake closing mechanism, pressure actuated means for unseating said inlet valves, means responsive to variations in pressure arising from closure of said intake closing mechanism controlling the pressure conditions in said pressure actuated means, and pressure responsive means controlling said intake closing mechanism.
23. In a compressor controlling mechanism, the combination including a compressor having high and low pressure cylinders, a receiver, intake controlling mechanism for said compressor including a valve having a chamber communicating therewith and a chamber communicating with the receiver, a connection between said chambers, means in said connection responsive to receiver pressure controlling the pressure conditions in the chamber communicating with said valve, suction inlet valves for the low pressure cylinder, suction inlet valves for a high pressure cylinder, plunger mechanism for unseating said last mentioned valves, pressure fluid connections between said plunger mechanism and said receiver, and means responsive to pressure conditions in the compressor arising from closure of said intake controlling valve controlling the pressure conditions in said pressure fluid connections.
24. In a compressor controlling mechanism, the combination including a multistage compressor having a plurality of cylinders and an intake, inlet valves for the high pressure cylinder thereof, intake closing mechanism, pressure actuated plunger mechanism for actuating said inlet valves, and means responsive either to a change in pressure conditions beyond the low pressure cylinder arising from the closure of said intake closing mechanism, or to pressure at a point beyond said intake closing mechanism, for supplying pressure fluid to said plunger mechanism.
25. In combination, a compressor having high and low pressure cylinders, intake controlling mechanism, inlet valve mechanism for the low pressure cylinder thereof, inlet valves for the high pressure cylinder, and means responsive either to pressure changes in said compressor beyond the low pressure cylinder arising from closure of said intake controlling mechanism or to the pressure changes in said inlet for controlling certain of said inlet valves.
26. In a compressor controlling mechanism, the combination including a multi-cylinder compressor having an intake, inlet valves for the high pressure cylinder thereof, intake closing mechanism, pressure actuated means for unseating said inlet valves, means responsive either to variations in pressure beyond one of said cylinders arising from closure of said intake closing mechanism or to pressure variations in said intake, for controlling the pressure conditions in said pressure actuated means, and pressure responsive means controlling said intake closing mechanism.
27. In a combination, a multi-cylinder compressor having an intake, intake closing mechanism, automatically acting means controlled by variations in pressure between two of said cylinders or in said intake and arising from the closure of said intake for progressively unloading said compressor cylinders, and manually operable means for subjecting said automatically acting means to either of said pressures.
28. In combination, a multi-cylinder compressor having an intake, intake closing

mechanism, and automatically acting means controlled by variations in pressure between two of said cylinders or in said intake and arising from the closure of said intake for 5 progressively unloading said compressor cylinders, and adjustable means for subjecting said automatically acting means to either of said pressures.

29. In combination, a multi-stage compressor having a plurality of compression chambers, an intake, an intake closing mechanism, automatically acting means controlled by variations in pressure in said compressor for unloading one of said chambers, and 15 means for alternatively connecting said controlling means to different parts of said compressor to vary the operation of the controlling means.

30. In combination, a compressor having 20 a plurality of compression chambers, unloading mechanism for each of the chambers, means for effecting variable sequential operation of said unloading mechanism comprising control means for each of said mechanisms each controllable by the same medium as the other, and means governed by the effects produced at various points in said compressor by the operation of one of said control means for controlling the operation of 25 the other.

31. In combination, a multistage compressor having a plurality of compression chambers and an intake, intake controlling mechanism, inlet valve mechanism for a stage 35 above the first, means for rendering said inlet valve mechanism inoperative, and means for unloading the stages of said compressor sequentially comprising a plurality of compressor discharge pressure actuated

control valves, one of said valves controlling 40 said intake controlling mechanism and another controlling the means for rendering said inlet valve operating mechanism inoperative, said last mentioned valve being provided with control mechanism governed by 45 changes in pressure conditions in the compressor arising from operation of said intake control mechanism.

32. In an unloading mechanism for compressors, a plunger movable to unload the 50 compressor, fluid pressure control means for said plunger including a valve, a diaphragm, a spring, said diaphragm and spring normally holding said valve closed, and connections from the opposite sides of said diaphragm respectively to a space wherein a sub-atmospheric pressure exists during running of the compressor unloaded, and a space 55 connected with the discharge side of the compressor.

33. In a compressor controlling mechanism, a valve controlling piston, means for controlling the movements of the latter including a valve, a connection with a source of compressor discharge pressure, a connection 60 with a space wherein a sub-atmospheric pressure exists when the compressor is run unloaded, a diaphragm operatively engaging said valve, and a spring tending to force said diaphragm in a direction to close said 65 valve, said first mentioned connection communicating with the side of said diaphragm toward said valve and said second mentioned connection with the opposite side of said diaphragm.

In testimony whereof I affix my signature.

FRED D. HOLDSWORTH.
